UNITED STATES PATENT OFFICE.

LOUIS F. HESS, OF ANSTED, WEST VIRGINIA, ASSIGNOR TO HESS DUSTLESS MINING MACHINE COMPANY, OF ANSTED, WEST VIRGINIA.

CUTTER-HEAD.

1,109,988.

Specification of Letters Patent.

Patented Sept. 8, 1914.

Application filed November 9, 1912. Serial No. 730,480.

To all whom it may concern:

Be it known that I, LOUIS F. HESS, a citizen of the United States, residing at Ansted, in the county of Fayette and State of West Virginia, have invented a new and useful Cutter-Head, of which the following is a specification.

One object of the present invention is to provide a cutter head for a mining machine, having a spiral rib, the rear face of which is so constructed as to afford an increased amount of space for the cuttings, thereby preventing the cuttings from being ground to powder as they are retracted by the spiral rib.

Another object of the invention is to provide a cutter head for a mining machine, having a spiral rib so constructed that a minimum amount of the power employed in driving the head, will be consumed in the operation of retracting the cuttings.

With the above and other objects in view which will appear as the description proceeds, the invention resides in the combination and arrangement of parts and in the details of construction hereinafter described and claimed, it being understood that changes in the precise embodiment of invention herein disclosed can be made within the scope of what is claimed without departing from the spirit of the invention.

In the drawing, Figure 1 shows the invention in side elevation, parts being sectioned, and Fig. 2 is an enlarged sectional detail in a longitudinal plane.

In carrying out the invention there is provided a tapered cutter head 1 provided with a spiral rib 2, the rib 2 comprising a front face 3 and a rear face 4. The front face 3 is disposed at an acute angle to the axis of the cutter head, and slants forwardly, the rear face 4 being disposed at an acute angle to the axis of the cutter head and slanting rearwardly. The faces 3 and 4 define an obtuse angle with respect to each other. Inserted into the front face 3 of the spiral rib 2 are cutting tools 5, and a bit 6 is carried by the forward end 7 of the head 1. As indicated at 8, the rear face 4 of the spiral rib 2 is concaved toward the axis of the cutter head. The concaved rear face 4 of the rib 2 slants from the outer edge 9 of one convolution 10 of the front face 3 to the inner edge 11 of an adjoining convolution 12 of the front face 3. Further, the

concaved face 4 is curved away from a line 14-14 connecting the points 9 and 11, as clearly shown in Fig. 2. Further, it is to be noted that the distance between the points 9 and 11, in one convolution of the rear face 4, is greater than the distance between the points 9^a and 11^a of the next forward convolution of the rear face 4, so that, in substance, the rear face 4 tapers circumferentially of the head, toward the forward end 7 of the head.

It is to be observed that when the cuttings are retracted by the spiral rib 2, the cuttings, as they move rearwardly, are permitted to expand transversely of the axis of the cutter head, owing to the concavity of the rear face 4, as indicated at 8. This feature will be clearly understood when the space which in Fig. 2, exists between face 8 and the line 14-14, is noted. Owing to the fact that the cuttings, as they are retracted, are permitted to expand transversely of the axis of the cutter head, and are not bound between the rear face 4 and the wall of the hole, a minimum amount of the power which is employed for the rotation of the cutter head is extended in the actual operation of retracting the cuttings.

It has been pointed out hereinbefore that the distance between the points 9 and 11 of one convolution of the face 4 is greater than the distance between the points 9^a and 11^a of a forward convolution of the face 4, the face 4 being of greatest width adjacent the butt of the head, and tapering, circumferentially of the head, toward the forward end 7 of the head. Consequently, the cuttings, as they are retracted, are not packed together longitudinally of the axis.

From all of the foregoing it will be obvious that the cuttings, while they are being retracted, are not compacted either transversely of the axis or longitudinally of the axis of the head, the result being that a minimum amount of the power used in rotating the head, goes to effect the retraction of the cuttings. Further, the cuttings are not comminuted, and the cutter head herein disclosed will be practically dustless in operation.

Having thus described the invention what is claimed is:

1. A cutter head for a mining machine, having a spiral rib comprising front and rear faces, the rear face slanting from the

outer edge of one convolution of the front face toward the inner edge of an adjoining convolution of the front face, the rear face being concaved toward the axis of the head.

2. A cutter head for a mining machine, having a spiral rib comprising front and rear faces, the rear face being concaved toward the axis of the head and away from a line joining the outer edge of one convolution of the front face with the inner edge of an adjoining convolution of the front face.

3. A cutter head for a mining machine, having a spiral rib the rear face of which is concaved toward the axis of the head and is tapered circumferentially of the head toward the forward end of the head.

4. A cutter head for a mining machine, having a spiral rib comprising front and rear faces, the rear face being concaved toward the axis of the head and away from a line joining the outer edge of one convolution of the front face with the inner edge of an adjoining convolution of the front face, the rear face being tapered circumferentially of the head toward the forward end of the head.

In testimony that I claim the foregoing as my own, I have hereto affixed my signature in the presence of two witnesses.

LOUIS F. HESS.
